CLAIM

The ornamental design for a wall mounted exercise rack, as shown and described.

DESCRIPTION

FIG. 1 is a top, front, right perspective view of a wall mounted exercise rack showing my new design;

FIG. 2 is a front view thereof;

FIG. 3 is a right side view thereof;

FIG. 4 is a left side view thereof;

FIG. 5 is top view thereof; and,

FIG. 6 is a top, front, left perspective view of the design thereof positioned on a wall shown as example environment. The broken lines immediately adjacent to the shaded area define the bounds of the claimed design and form no part thereof. The broken lines depicting the remainder of the wall mounted exercise rack show portions that form no part of the claimed design. The broken lines depicting the example environment of a wall shown in FIG. 6 show features that form no part of the claimed design.
